UNITED STATES PATENT OFFICE

GUSTAV A. SCHETTLER, OF LEEDS, ENGLAND, ASSIGNOR TO THE TURNER TANNING MACHINERY COMPANY, OF PORTLAND, MAINE, A CORPORATION OF MAINE

LEATHER STRETCHING MACHINE

Application filed September 8, 1926, Serial No. 134,191, and in Great Britain September 29, 1925.

This invention relates to apparatus for stretching hides, skins and leather and is illustrated as embodied in an apparatus particularly adapted to the stretching of butt-bends for use in the manufacture of leather belting.

In leather stretching apparatus a plurality of frames is commonly provided upon which pieces of leather may be stretched while in wet or, as it is termed, sammied condition and allowed to remain in stretched condition until they have dried. Subsequently the dried pieces of leather are removed from the frames and the frames utilized for other stretching operations. While it is a matter of considerable importance that these frames should be of such a construction as to permit the pieces of leather to be readily secured to the frames and removed therefrom, it is still more important that provision be made for facilitating the stretching of leather in various directions and along a plurality of lines and that the stretcher frames should be readily adjustable to pieces of leather of various sizes and to stretching operations along lines the location of which may be varied during stretching operations along other lines.

To these ends and in accordance with important features of the invention means are provided in connection with stretcher frames for stretching a piece of leather in directions transverse of its length dimension comprising members readily detachable from and attachable to a stretcher frame and slidable on the frame for adjustment in directions toward and from each other, whereby pieces of leather of different sizes and contours are quickly secured for stretching, other means being provided for stretching operations in directions toward or from either end of the piece of leather, that is, in the direction of the length of the piece of leather, the construction and arrangement being such that the lines of transverse stretching may be properly accommodated to the leather as it is being lengthened by longitudinal stretching operations. In the illustrated construction the means for stretching the leather in directions transverse of its length are embodied in pairs of clamping members, the members

of each pair being freely adjustable in directions toward and from each other, means being provided unconnected to the clamping members and simultaneously operable to move the members away from each other to place the leather under a stretching strain, the clamping members being also freely movable on the stretcher frame to adjust themselves to new locations made necessary by the stretching of the piece of leather in the lengthwise direction. Conveniently, and as illustrated, tubular members support the clamping members and are slidable upon stretcher bars which serve as parts of the stretcher frame designed to put the piece of leather under lengthwise tension. For operating the clamping members on each tubular member there is preferably provided a member having its opposite ends reversely screw-threaded and adapted to engage correspondingly screw-threaded elements designed to operate the clamping members simultaneously away from each other upon rotation of the screw-threaded member.

Commonly there is provided an overhead runway or track for supporting a plurality of stretcher frames, the construction and arrangement being such that the frames are removed from the track or placed thereon by utilizing for the purpose an open end of the track or a gap in the track. Both of these constructions are objectionable for the reason that one or more of the stretcher frames may escape proper control and ride off an end or through a gap of the track. It is an important feature of this invention that the illustrated stretcher frames may be readily attached to or disengaged from a continuous track at any point in the length thereof. For this purpose there is provided for engaging the runway or overhead track a roller trolley or truck which remains with the track while the frame is disengaged from the trolley to be re-engaged therewith after receiving a stretched piece of leather. Conveniently means is provided for facilitating this disconnection of the stretcher frame from its trolley. In the preferred form of the invention this means comprises a cam located in predetermined relation to the track

and to a carrier or supporting table for receiving the stretcher frame from the track and for returning it thereto after a piece of leather has been stretched on the frame.

A further important feature of the invention resides in the provision of an improved carrier or supporting table for receiving the stretcher frames successively from the runway or overhead track, positioning the frames with respect to a stretching machine, and returning the frames with pieces of leather stretched thereon to the runway or track. In the most widely used apparatus for the stretching of leather, the carrier or supporting table is mounted upon a platform, upon which the workers are also obliged to stand, in order that the frames may be removed readily from the overhead runway. Hence the carrier or supporting table cannot be readily shifted nor can it be located at any desired point in the length of the track without adjustment of the platform to the exact height of the runway. To overcome this disadvantage the illustrated carrier or supporting table is constructed and arranged with a movable portion capable of lifting the stretcher frame to various heights to connect it with the track at any desired point, and to lower the stretcher frame from the track and into a horizontal position where the stretched piece of leather may be removed and a new piece of work inserted. Conveniently the carrier or supporting table is provided with a member positioned to receive the stretcher frame as the latter moves along the track, this member being so supported as to move downwardly after the disconnection of the frame from the track and to serve as a pivot about which the frame turns to horizontal position for the reception of the new piece of work. In the illustrated carrier or supporting table the described frame receiving member is carried by a pair of counterbalanced levers arranged to move in parallelism in raising and lowering the stretcher frame to connect the stretcher frame with the track or to remove it therefrom, means being also provided under the control of the operator for shifting one of the levers to tilt the stretcher frame thereby completing its disconnection from its associated trolley or to reconnect it with said trolley. In the preferred construction the means for thus moving one of the levers comprises an eccentric mounting for the lever arranged to be controlled by a manually operable lever. Preferably the stretcher frame and the movable levers are locked when the frame has reached horizontal position by means automatically operative for the purpose. Conveniently, too, means is provided for unlocking simultaneously both the stretcher frame and the levers so that the frame may be tilted into vertical position and the levers operated to raise the frame into

position to be connected again with the overhead runway or track.

These and other features of the invention and novel combinations of parts will be described in detail and pointed out in the appended claims.

In the drawings,

Fig. 1 is a plan of a stretching frame constructed in accordance with the invention;

Fig. 2 is a side elevation of the same;

Fig. 3 is a longitudinal section through one end of one of the lateral stretching devices;

Fig. 4 is a cross section of a detail herein-after particularly referred to;

Fig. 5 is a side elevation of a stretching frame, carrier or support constructed in accordance with the invention, in the raised position, and in association with a stretching frame and an improved trolley for suspending said frame from a runway;

Fig. 6 is a side elevation;

Fig. 7 is an end elevation as viewed from the right of Fig. 6, of said carrier or support in the lowered position;

Fig. 8 is a plan of the same;

Fig. 9 is a perspective view of one type of stretching machine which may be used in stretching operations; and

Fig. 10 is another view of the apparatus for stretching and drying leather shown in Fig. 5, looking from the right in the latter figure.

Figs. 3 and 4 are drawn to a larger scale than the remaining figures.

Referring first to Figs. 1 to 3, according to the construction shown therein, the lateral stretching devices of the illustrated stretching frame F comprise tubular bars 1 which are arranged transversely of and have shoes 2 to fit upon and slide along the longitudinal stretcher bars 3 of the frame thereby enabling their position to be varied between the end bars or plates 4 and 4a of the frame. Conveniently the bars 3 are of standard channel iron and the shoes 2 are constructed to fit upon the upper limbs of the channels as represented in Fig. 3. Extending through each tubular bar is a rod 5 which at its opposite ends is screw threaded with right and left hand threads respectively. The ends of the rod are slightly reduced and have pins 6 therein (although they may be squared or otherwise formed) for application of a handle (not shown) or other instrument by which rotation of the rod can be effected.

For some distance inwards from each of its ends each tubular bar 1 is formed with a slot 7 and slidably over the slotted portion is a clamp member which is engaged by a suitable nut on the screw-threaded end of the rod 5. To this end the nut may consist of a sleeve 8 provided with a lug or projection 9 (Fig. 3) which works in the slot 7 in order to prevent rotation of the nut. The nuts are located on the inside of the clamps and

- merely engage the latter by contact so that the clamps are freely floating and readily movable toward and from each other by hand. An important advantage is that the screw-threaded rod 5 with its nuts and the clamps can float lengthwise of the tubular bar 1 for purpose of location and that in operation the two clamps are moved outwards simultaneously.
- 10 Each clamp preferably consists of a sleeve 10, see particularly Fig. 3, constructed to fit and slide upon the tubular bar and having integral with it a serrated or toothed jaw 10a with which a correspondingly serrated or toothed movable jaw or clamp plate 11 contacts to hold the leather. Associated with these parts is an eye-bolt 12 which is engaged by a nut 13 and when the clamp is in position it slides on the rod 5 and in the slot 7.
- 15 A compression spring 14 is interposed between the said jaw members 10a and 11 so as to raise the jaw or plate 11 when the nut is slackened. The sleeve 10 is furnished with a conical dowel 15 which extends into a corresponding hole in the jaw or plate 11 in order to prevent relative turning movement between the two members. Actually the nuts 8 make contact with the eye-bolts 12 to move the pair of clamps at the ends of the rod 5 outwards away from each other when the rod 5 is turned for stretching the material laterally and to permit of this the sleeves 10 are formed with grooves 16 for reception of the projections 9.
- 20 Clamping devices 17 in each of two end plates of the frame F are also adjustable in position. Heretofore the clamps in one plate only were so adjustable, the disadvantage of this being that one end of the hide had to be cut off straight or spaces had to be cut for the bolts of the clamps. By making the clamps on both end members adjustable in position they can be located to suit the shape of the hide and thereby avoid the waste caused by cutting the hide to suit the clamps.
- 25 As a rule the neck end of the hide is nearly straight but some cutting has usually been necessary to enable this end to be properly clamped in the frame. The end plates 4 and 4a in the improved frame are provided with slots 18 and 19, respectively, for the passage of the bolts of the clamp devices 17 which latter may be of the usual form, i. e., comprising two correspondingly toothed or serrated jaws resembling the members 10 and 11 except in that the lower jaws are formed without the sleeve portions essential to the members 10. The end plate 4 is, of course, normally movable on the bars 3, and the member 4a is stationary on said bars.
- 30 A further feature of the improvement resides in the means employed for rigidly fixing the said movable end plate 4 on the stretcher bars 3 after the hide has been stretched to the desired extent. Heretofore
- this has been effected by eccentric devices associated with said member and adapted to bind on the frame bars 3. This arrangement was disadvantageous in that when the stretching frame F was disconnected from the stretching machine there was a tendency for the hide to contract until the grip of the eccentrics became effective. Referring to Figs. 1 to 4, instead of the eccentric devices we provide two cramps each of which comprises a saddle 20 and a plate 21 fitted with friction blocks 22 and 23 respectively, which are of hard wood though any other suitable material may be utilized for the purpose. Screws 24 are passed through holes in the plate and into corresponding tapped holes in the saddle and the latter is recessed to receive the end plate 4 and is attached thereto by means of nut and bolt fastenings 25 (Fig. 4), the blocks 22 being correspondingly counterbored to receive the heads of the bolts. Normally the cramps are free to slide on the channel members 3 until the hide has been stretched to the required extent whereupon the cramps are caused to grip the channel members 3 by means of the screws 24. The saddles 20 are constructed so as to overlap the channel members 3 on the inside and thus constitute guides during movement of the end plate and cramps lengthwise of the stretching frame F on the channel members 3, and further are formed with projections for the reception of screws 26 with which corresponding projections on the cramp plates 21 make contact so as to prevent the saddles and cramp plates from spreading on the inside under the action of the screw 24. The end plate 4a is fixedly attached in any convenient manner to blocks 27 suitably fixed on the bars 3. The said plate abuts against a shoulder 28 on the blocks 27 and each of the latter has another shoulder 29 thereon which abuts against the end of the corresponding bar 3 in order to avoid shearing stresses on the fastening means.
- 35 Referring now to Figs. 5 to 8, the carrier or support S for successive stretcher frames F comprises a pair of standards 30 connected by the rods 31 and having fulcrumed thereon two systems of levers or arms 32 and 33 which operate with a parallel motion. The upper levers or arms 32 are mounted on a spindle 34 suitably supported in the standards and may be connected by a tie rod 35. The lower levers or arms may be similarly mounted, but, for a purpose hereinafter explained, are 110 preferably freely mounted upon eccentrics 36 fast on a cross shaft 37 fitted rotatably in the standards. The upper and lower levers or arms on opposite sides of the carrier or support S are connected by a vertical support 38 each of which carries brackets 39 to which a horizontal bar 40 is fixed. Counterweights 41 mounted on arms 42 attached to the levers 32 are provided substantially to balance the movable part of the carrier S when a stretch- 115 120 125 130

ing frame F is supported thereon. For use in conjunction with the carrier or support S the stretching frame F (which for convenience may be regarded as that previously described herein) may be fitted with wheels, rollers, clips or other devices which may be disposed approximately centrally on the main bars or other parts of the frame. For example, grooved wheels 43 (see also Figs. 1 and 2) may be provided on the stretcher bars 3, each wheel being rotatably supported by the adjacent bar and by a bearing 44 attached to the bar.

The improved trolley T hereinbefore referred to may consist of a carriage 45 (Fig. 5) fitted with wheels 46 to travel along a runway constituted by a girder 47. Commonly the girder 47 is of considerable length and is supported by being fixedly attached to the ceiling of the room containing the leather stretching apparatus. The carriage 45 is also provided with a swivel hook 48 or equivalent device adapted to engage with the end member 4a of the stretcher frame F for the purpose of carrying the latter. To this end the end plate 4a of the frame F may have a hole 49 therein (see Fig. 8) for reception of the hook. A safety catch or some similar member is associated with the hook in order to prevent accidental detachment of the frame F during transport. Conveniently the catch consists of a spring controlled pivoted catch 50 which, when the frame is suspended from the trolley T, engages the upper edge of the plate 4a. Fixed on the girder 47 above and in a median position with relation to the transverse dimension of the carrier or support S which is to receive the frame F for the stretching operation is a skate cam 51 with which the free end of the catch 50 engages when the trolley T and a given stretcher frame F come into position over the carrier S. This engagement operates the catch to permit the removal of the frame F from the hook 48.

In use, the carriage or support S is situated in front of a stretching machine shown at 500 in Fig. 9 as of the usual hydraulic type. When a frame F is being transferred to or removed from the support S, the movable part of the support occupies the raised position shown in Fig. 5. When the frame F suspended from the trolley T is brought into position, the grooved wheels 43 on the frame F run on the bar 40 which is situated at the right height to receive them and take the weight of the frame. In order to free the frame F from the hook 48 means may be provided whereby it may be tilted to some extent subsequently to its release by the aforesaid catch 50. This is the purpose for which the levers or arms 33 are pivoted on the eccentrics 36. As shown, there is provided in association with the eccentrics a horizontal pusher bar 52 fixed on the vertical supports

38 so as to engage the stretcher frame T adjacent to the lower end thereof when the latter occupies the position shown by full lines in Fig. 5. By rotating the eccentrics the effective length of the levers or arms 33 is increased so that the pusher bar 52 acts upon the stretcher frame F and tilts it about the bar 40 as represented by dot and dash lines. A hand lever 53 is provided on the eccentric shaft 37 for effecting the rotation of the eccentrics 36, the operative movement being in the direction indicated by the arrow in Fig. 5. This hand lever is preferably a push fit on one end of the eccentric shaft and adjustably connected to the adjacent eccentric so as to enable it to be fixed in the most convenient position for use. To this end said lever is provided with a slotted segment 54 through which a fastening 55, such as a screw or a stud engaged by a clamping nut (not shown), is passed into the eccentric. The stretching frame can thus be turned on the bar 40 and at the same time the movable structure can be lowered to bring the frame down to a substantially horizontal position level with the top of the stretching machine, whereupon the hand lever may be moved in the reverse direction to that aforesaid so as to enable the members 38 to stand vertically, and thus support the bar 40 and the weight of the frame thereon, as represented in Fig. 6. The movement of the hand lever in either direction may be limited by means of a segment 56 formed with abutments 57 and attached to the adjacent standard 30 for engagement by a lug or projection 58 on the eccentric. The aforesaid movement of the stretching frame F and movable part of the carrying structure S may be effected by hand and when the frame F is in the horizontal position it may be connected to the stretching machine 500 (Fig. 9) either automatically or by hand. The frame F is prevented from endwise displacement on the carrier in one direction by engagement of the bearings 44 with abutments 59 (Fig. 6) fixed on a transverse bar 60 attached to the brackets 39, and in the opposite direction by the engagement of the wheels 43 with the bar 40.

Suitable means are provided for locking each successive frame F on the carrier or support S, and further means are furnished for locking the lever systems 32, 33 against movement during the stretching operation. For example, hook levers 61 fulcrumed on the standards 30 are provided to engage the channel members 3, said levers being normally held in the locking position by springs 62 (Fig. 7) interposed between their lower ends and the standards. As the frame F assumes the horizontal position on the carrier or support the channelled stretcher bars 3 engage the bevelled ends of the hook levers or catches 61 and thus move them outwards, against the action of the springs 62 until the

lower webs of the channeled part of each bar 3 pass below the hook 61 whereupon the hooks snap into locking engagement with the bars 3. Similarly a hook lever 63 (Figs. 6 and 7) is fixed on a rockshaft 64 carried by bearings 65 adjacent to one of the levers or rams 33 of the lower system, this hook lever 63 being also held in its operative position by a spring 66 interposed between its outer end and the adjacent bearing 65 so that when the movable lever structure swings down, the hook lever 63 first yields and then snaps into engagement with the said lever or arm. For operating the hook levers 61 and 63 to free the movable lever structure 32, 33 and the frame F, the rockshaft 64 is fitted with a treadle 67 rigidly secured to the shaft 64 and with an arm 68 which is connected by a link 69 to one of a pair of cam segments 70 fixed on opposite ends of a transverse rockshaft 71 so as to act upon the lower ends of the levers 61, said rockshaft 71 being supported by suitable bearings on the standard. Normally the treadle is held raised with the cam segments in the inactive position by the spring 66. Upon depression of the treadle after a stretching operation, the hook levers 61 and 63 are operated simultaneously to release the lever systems 32, 33 and also the frame F. The latter may then be turned to the vertical position and raised, re-engaged with the holding means or hook 48 on the trolley T, and then run off the horizontal bar 40, while another frame F is being run on.

The frames are brought along in succession to the stretching machine as will be understood. In addition to the carrier or support S associated with the stretching machine, similar carriers or supports S may be used at other points in the circuit to receive the frames F from the runway and thus serve as auxiliary tables to carry the frames F while butts or hides are being taken therefrom and others placed therein.

It is to be understood that the invention contemplates as one of its features the provision of a plurality of carriers such as a carrier S for receiving, moving and holding a succession of frames F, one or more of the carriers being used in association with a stretching machine while other carriers may be used solely as a table for removing pieces of work and placing other pieces on frames which are later moved to a carrier associated with a stretching machine where the stretching is performed. By thus using a number of these carriers S as lifting devices and preparing tables in convenient position along the runway for the purpose of removing frames F from the trolleys T and putting them into a horizontal position for the operator to remove the stretched and dried leather and insert a new piece of leather into each frame preparatory to a stretching operation,

the general operation is facilitated since the replacement of the material in the frame takes much longer than the actual stretching operation in the machine 500. Therefore, if a number of carriers S are provided for use as tables, the output of the stretching machine can be proportionally increased.

Having described my invention, what I claim as new and desire to secure by Letters Patent of the United States is:—

1. In an apparatus for stretching leather, a frame upon which a piece of leather may be stretched, said frame having side and end bars, means associated with the frame operative to engage opposite end portions of the piece of leather to stretch it in one direction, means adapted to engage opposite side edges of the piece of leather, means for operating the last-mentioned leather engaging means to stretch the piece of leather transversely of the stretching effected by the first-mentioned means, and supports for the last-mentioned leather engaging means slidable on the side bars of the frame and readily attachable thereto and detachable therefrom.

2. In an apparatus for stretching leather, a frame upon which a piece of leather may be stretched, said frame having side and end bars, means adapted to engage opposite ends of the piece of leather to stretch the leather lengthwise, clamps freely slidable at each side of the frame for ready engagement with the side edges of the piece of leather, means to operate the clamps to effect stretching of the piece of leather transversely of the lengthwise stretching, and supports for the clamps having open-ended shoes for slidably and detachably engaging with the side bars of the frame.

3. In an apparatus for stretching leather, a frame adapted to support a piece of leather to be stretched, means at each end of the frame for engaging and stretching the piece of leather in one direction, clamping members at each side of the frame for engaging the side edges of the piece of leather for stretching the leather in another direction, said frame having secured thereto supporting bars upon each of which a clamping member is freely slidable at each end thereof, and means for simultaneously operating the pair of clamping members upon each bar.

4. In a frame for stretching a piece of leather, means at each end of the frame for engaging and stretching a piece of leather in one direction, clamping members for engaging opposite side edges of the piece of leather, means slidably secured to the frame for mounting the clamping members in pairs for freely slidable movement in directions both sidewise and endwise of the frame, and means for moving both clamping members of each pair simultaneously away from each other to effect stretching of the leather, the clamping members being freely movable with respect

to their moving means when not engaged with a piece of leather.

5. A frame for use in the stretching of leather comprising end members having means for engaging opposite ends of a piece of leather, clamping members for engaging side edge portions of the piece of leather, members extending transversely of the frame and slidably secured thereto for supporting 10 the clamping members in pairs, the clamping members of each pair being both freely movable toward and from each other upon their supporting member, and means for moving the clamping members of each pair only in 15 directions away from each other, to effect stretching of the piece of leather.

6. In a frame for stretching leather, means at opposite ends of the frame for engaging and stretching a piece of leather in a longitudinal direction, clamping members for engaging opposite side edges of the piece of leather for stretching it in a direction substantially at a right angle to the said direction, supports for the clamping members extending crosswise of the frame and connecting the clamping members in pairs, and a member having reversely screw-threaded ends for engaging with the clamping members to move them simultaneously away from each 30 other upon rotation of the screw-threaded member.

7. In a frame for stretching pieces of leather, means at each end of the frame for engaging opposite ends of a piece of leather for 35 to stretch it in a longitudinal direction, clamping members for engaging the opposite side edges of the piece of leather for stretching it in a transverse direction, members extending crosswise of the frame for connecting 40 the clamping members in pairs, means for mounting the connecting members for sliding movement toward and from opposite ends of the frame, and means for mounting the clamping members for sliding movement upon their 45 connecting members.

8. A frame for stretching pieces of leather comprising end members having means for engaging opposite end portions of a piece of leather, a pair of bars connecting the end members, clamping members for engaging opposite side edges of the pieces of leather, supporting members for the clamping members extending transversely of said bars, means for slidably mounting the supporting 55 members on said bars, means for slidably mounting the clamping members on their supporting members, and means for operating the clamping members in pairs on their supporting members to stretch the piece of leather between its side edges.

9. A frame for stretching pieces of leather comprising end members provided with means for engaging opposite end portions of a piece of leather, a plurality of bars connecting the end members, a plurality of tu-

bular members extending transversely of the bars and connected thereto for sliding movement thereon, clamping members mounted upon the opposite ends of the tubular members and adapted to engage opposite side edges of the piece of leather, each tubular member having extending therethrough a rod the opposite ends of which are screw threaded in reverse directions, and nut members having 70 interiorly screw-threaded portions for engagement with the screw-threaded portions of the rods so that upon rotation of the rods in one direction the nut members will engage with the clamping members to move them 75 simultaneously in directions away from each other.

10. A frame for stretching pieces of leather which comprises end pieces having means for engaging opposite end portions of a piece of leather; clamping members for engaging opposite side edge portions of the piece of leather, a rod having right and left-handed threaded portions extending transversely of the frame for operating the clamping members, and nuts associated respectively with the clamping members and arranged in engagement with the adjacent screw-threaded end of the rod, each nut being loose from its associated clamping member so that the clamping members are free for adjustment to 85 suit the dimensions of the piece of leather on the frame, the construction and arrangement being such that upon rotation of the screw-threaded member in one direction the clamping members are simultaneously moved 90 away from each other to apply tension to the piece of leather, while upon rotation of the screw-threaded member in the other direction the clamping members are released from the nuts through withdrawal of the latter so that the clamping members become 95 freely slidable toward and from each other upon the rod.

11. A frame for stretching a piece of leather comprising end pieces for engaging opposite end portions of a piece of leather, clamp members for engaging opposite lateral edges of the piece of leather, transverse tubular members for connecting the clamping members in pairs, each tubular member being slotted for a considerable distance inwardly from each of its ends, a plurality of bars connecting the end pieces of the frame, shoe members connected to the tubular members and adapted to engage the bars so that the tubular members may slide in longitudinal directions upon the bars, rods extending through the tubular members and each provided with right- and left-handed screw-threaded portions at its opposite ends, and nuts upon the screw-threaded 110 ends of each rod, said nuts having projections adapted to work in the slots in the tubular members and each nut being located on the inner side of a clamp member to engage the 115 same merely by contact therewith so that 120

upon rotating the rod in one direction the nuts recede from the clamp members leaving them free to slide in the slots and upon rotation of the rod in the opposite direction the nuts contact with the clamping members to shove them away from each other to apply tension to the piece of leather engaged by the clamping members.

12. A frame for stretching pieces of leather comprising end pieces having means for engaging opposite end portions of a piece of leather, a plurality of bars for connecting the end pieces, one of the end pieces being securely attached to the bars while the other end piece is slidably on the bars in directions toward and from the other end piece, said movable end piece being provided at each end with a saddle and a cramp plate respectively fitted with friction blocks for engagement with the bars, and screws passed through the cramp plate and into engagement with the saddle plate for tightening the saddle and cramp plates upon the bar to hold the end piece in its adjusted position.

13. In an apparatus for stretching pieces of leather comprising an overhead runway for supporting a plurality of stretcher frames, a carrier or supporting table operable to lift the frames one at a time toward the runway or to lower them therefrom, said carrier or supporting table comprising standard and a member pivoted to the standard and movable in a vertical direction for engaging and supporting a frame so that upon movement of the member the frame may be lowered or raised, the member being so constructed as to permit the frame to turn thereon as on a pivot whereby the frame may assume either a horizontal position with respect to the carrier or supporting table or a vertical position in which it may be again connected to the runway.

14. In an apparatus for stretching pieces of leather comprising an overhead runway for supporting a plurality of stretcher frames, a carrier or supporting table operable to lift the frames one at a time toward the runway or to lower them therefrom, said carrier or supporting table comprising a pivoted member movable about a horizontal axis and having means connected therewith for engaging and supporting a frame so that upon movement of the pivoted member the frame may be lowered or raised, and means for maintaining the pivoted member in vertical position during up-and-down movements thereof, the supporting means for the frame being so constructed as to permit the frame to turn thereon as on a pivot whereby the frame may assume either a horizontal position with respect to the carrier or supporting table or a vertical position in which it may be again connected to the runway.

15. In an apparatus for stretching pieces of leather comprising an overhead runway for supporting a plurality of stretcher

frames, a carrier or supporting table operable to lift the frames one at a time toward the runway or to lower them therefrom, said carrier or supporting table comprising a member for supporting a stretcher frame so that upon movement of the member the frame may be raised or lowered, said supporting member being adapted for ready engagement of a stretcher frame during sidewise movement of the frame, and said carrier or supporting table further comprising means operative to raise and to lower the stretcher frame supporting member, the stretcher frame being rotatable upon its supporting member from a vertical to a horizontal position.

16. In an apparatus for stretching pieces of leather comprising an overhead runway for supporting a plurality of stretcher frames, the combination of a carrier or supporting table operable to lift frames one at a time toward the runway or to lower them therefrom, said carrier or supporting table comprising a member adapted for ready engagement with a stretcher frame to support it during sidewise movement of the frame while it is still connected to the runway and said carrier or supporting table further comprising a pivoted member operative to raise and to lower the stretcher frame supporting member, the stretcher frame being rotatable upon its supporting member from a vertical to a horizontal position, and means for locking the stretcher frame in horizontal position.

17. In an apparatus for stretching pieces of leather comprising an overhead runway for supporting a plurality of stretcher frames, the combination of a carrier or supporting table operable to lift frames one at a time toward the runway or to lower them therefrom, said carrier or supporting table comprising a member by which a stretcher frame may be readily engaged and supported while it is being raised or lowered and said carrier or supporting table further comprising a member operative to raise and to lower the stretcher frame supporting member, the stretcher frame being rotatable upon its supporting member from a vertical to a horizontal position, and means for locking the stretcher frame in horizontal position and its supporting member in its lowered position, said locking means being readily releasable to permit restoration of the stretcher frame to the runway.

18. In an apparatus for stretching pieces of leather comprising an overhead runway for supporting a plurality of stretcher frames, the combination of a carrier or supporting table operable to lift frames one at a time toward the runway or to lower them therefrom, said carrier or supporting table comprising a member upon which a stretcher frame may readily engage and be supported.

during sidewise movement of the frame while it is still connected to the runway and said carrier or support further comprising a pivoted member operative to raise and to lower 5 the stretcher frame supporting member, the stretcher frame being rotatable upon its supporting member from a vertical to a horizontal position, means for locking the stretcher frame in horizontal position and the pivoted member of the carrier in its lowered position, and means for readily releasing the locking means to permit restoration of the stretcher frame to the runway.

19. In an apparatus for stretching pieces 15 of leather comprising an overhead runway for supporting a plurality of stretcher frames, the combination of a carrier or supporting table operable to lift frames one at a time toward the runway or to lower them 20 therefrom, said carrier or support comprising a bar disposed horizontally to receive a stretcher frame from the runway, each stretcher frame having means between its ends for engaging said bar so that the frame 25 may pivot on the bar in moving between horizontal and vertical positions, and means for supporting the bar operative also to lift and to lower the bar, said supporting means being provided with a counterweight which 30 serves to balance also the weight of the bar and of the stretcher frame while the latter is supported by the bar.

20. In an apparatus for stretching pieces 35 of leather comprising an overhead runway for supporting a plurality of stretcher frames, a carrier or supporting table operable to lift the frames one at a time toward the runway or to lower them therefrom, said carrier or supporting table comprising a bar 40 disposed horizontally to receive a stretcher frame from the runway, a vertically disposed member for supporting the bar, and a system of parallel levers for supporting the vertical member, said levers being provided 45 with a counterweight which serves to balance the weight of the vertical member, the levers, and the stretcher frame while the latter is supported by the carrier or supporting table.

50 21. In an apparatus for stretching pieces of leather comprising an overhead runway for supporting a plurality of stretcher frames, the combination of means for securing 55 the stretcher frames to the runway, and means for releasing each stretcher frame from the runway prior to removal therefrom.

22. In an apparatus for stretching pieces 60 of leather comprising an overhead runway for supporting a plurality of stretcher frames, the combination of means for securing the stretcher frames to the runway, and a cam member at a predetermined point in 65 the runway for causing release of the stretch-

er frame from the runway so that the former may be removed from the latter.

23. In an apparatus for stretching pieces of leather comprising an overhead runway for supporting a plurality of stretcher frames, the combination of means for securing the stretcher frames to the runway, and means supported stationarily with respect to the runway for releasing the stretcher frame from the runway. 70

24. In an apparatus for stretching pieces of leather comprising an overhead runway for supporting a plurality of stretcher frames, the combination of a carrier or supporting table operable to lift frames one at a time toward the runway so that they may be connected thereto or to lower them therefrom, said carrier or supporting table comprising two sets of levers, a vertically disposed member connecting the levers and operating to maintain them in parallelism, said member serving also as a support for a stretcher frame in removing the frame from the runway and in returning it thereto, and means for shifting the vertical member out of its vertical plane, thereby tilting the stretcher frame about a transverse axis, thus disconnecting the stretcher frame from the runway. 75

25. In an apparatus for stretching pieces 90 of leather comprising an overhead runway for supporting a plurality of stretcher frames, the combination of a carrier or supporting table operable to lift frames one at a time toward the runway so that they may be 95 connected thereto or to lower them therefrom, said carrier or supporting table comprising two sets of levers, a vertically disposed member connecting the levers and operating to maintain them in parallelism, said member serving also as a support for a stretcher frame in removing the frame from the runway and in returning it thereto, an eccentric mounting for one set of levers, and means for operating the eccentric to shift the vertical member out of its vertical plane, thereby tilting the stretcher frame about a transverse axis, thus disconnecting the stretcher frame from the runway. 100

26. In an apparatus for stretching pieces 115 of leather comprising an overhead runway for supporting a plurality of stretcher frames, the combination of a carrier or supporting table operable to lift frames one at a time toward the runway so that they may be 120 connected thereto or to lower them therefrom, said carrier or supporting table comprising two sets of levers, a vertically disposed member connecting the levers and operating to maintain them in parallelism, a bar carried by the vertical member to serve as a support for a stretcher frame in removing the frame from the runway and in returning it thereto, an eccentric mounting for 125 one set of levers, and a manually operable 130

lever for operating the eccentric mounting to shift the vertical member out of its vertical plane, thereby tilting the stretcher frame about the axis of its supporting bar and thus disconnecting the stretcher frame from the runway.

27. In an apparatus for stretching pieces of leather comprising an overhead runway from which a plurality of stretcher frames 10 may be suspended, the combination of a trolley for each stretcher frame adapted to connect the stretcher frame to the runway for movement therealong, said trolley and said stretcher frame having interconnecting means 15 by which the latter is supported by the former, a safety catch for preventing disconnection of the frame from the trolley, a carrier or supporting table for receiving in succession stretching frames from the runway, a stationary cam located centrally over one end of the carrier or supporting table and operative to release the safety catch, thereby permitting the stretcher frame to be detached from the trolley, said carrier or supporting table comprising a bar for receiving and supporting each stretcher frame in turn, and means 20 for tilting the stretcher frame after it has received support by the supporting bar to detach the stretcher frame from the trolley, thus permitting it to be lowered from the trolley.

28. In an apparatus for stretching pieces of leather comprising an overhead runway the combination of a plurality of stretcher frames adapted to be suspended from the runway, a trolley for each stretcher frame adapted to connect the stretcher frame to the runway for movement therealong, said trolley having a hook and said stretcher frame having an end piece provided with an opening for receiving the hook, a safety catch for holding the end piece of the stretcher frame on the hook, a carrier or supporting table for receiving in succession stretching frames 40 from the runway, a stationary cam located centrally over one end of the carrier or supporting table and operative to release the safety catch, thereby permitting the stretcher frame to be detached from the hook, said carrier or supporting table comprising a bar for receiving and supporting each stretcher frame in turn, and means for tilting the stretcher frame after it has received support by the supporting bar to detach the stretcher frame from the hook, thus permitting it to be lowered from the trolley.

29. In an apparatus for stretching pieces of leather comprising an overhead runway for supporting a plurality of stretcher frames, the combination of a trolley for each stretcher frame, said trolley being movable along the runway and provided with means for detachably supporting a stretcher frame, a carrier or supporting table for lifting a 55 stretcher frame into position to be engaged

by the supporting means and also for supporting the stretching frame while it is being disengaged from the supporting means and means associated with the carrier or supporting table to cause disengagement of the 70 stretcher frames from the trolley.

30. In an apparatus for stretching pieces of leather comprising an overhead runway for supporting a plurality of stretcher frames, the combination of a trolley for each 75 stretcher frame, said trolley being provided with wheels adapted to run on the runway and also with a hook for detachably supporting a stretcher frame, a carrier or supporting table for lifting a stretcher frame into position to be engaged by the hook and also for supporting the stretcher frame while it is being disengaged from the hook, and means mounted on the carrier or supporting table 80 for causing the stretcher frames to separate 85 each from its supporting hook.

31. In an apparatus for stretching pieces of leather comprising an overhead runway for supporting a plurality of stretcher frames, a carrier or supporting table for removing the stretcher frames one at a time and for returning them to the runway, said carrier or support comprising standards having supporting surfaces for the stretcher frame when the latter is in a horizontal position, a pair of levers pivoted to the standards, and a vertically disposed member connected to the levers in such a way as to maintain them in parallel relation, said vertical member serving as a support for a stretcher frame 90 while the latter is being removed from and returned to the runway and serving also in connection with the supporting surfaces on the standards to support the stretcher frame 95 when in horizontal position. 105

32. In an apparatus for stretching pieces of leather comprising an overhead runway for supporting a plurality of stretcher frames, a carrier or supporting table for removing the stretcher frames one at a time and for returning them to the runway, said carrier or supporting table comprising standards having supporting surfaces for the 110 stretcher frame when the latter is in a horizontal position, a pair of levers pivoted to the standards, and a vertically disposed member connected to the levers in such a way as to maintain them in parallel relation, said vertical member comprising a bar to serve as a support for a stretcher frame while the latter is being removed from and returned to the runway and serving also in connection with the supporting surfaces on the standards to support the stretcher frame when in horizontal position, and means on the carrier for preventing endwise movement of the stretcher frame while it is in horizontal position. 115 120

33. In an apparatus for stretching pieces of leather comprising an overhead runway for supporting a plurality of stretcher frames, 130

- the combination of a carrier or supporting table for removing the stretcher frames one at a time and for returning them to the runway, said carrier or support comprising standards having supporting surfaces for the stretcher frame when the latter is in a horizontal position, a pair of levers pivoted to the standards and a vertically disposed member connected to the levers in such a way as to maintain them in parallel relation, said vertical member serving as a support for a stretcher frame while the latter is being removed from and returned to the runway and serving also in connection with the supporting surfaces on the standards to support the stretcher frame when in horizontal position, and means on the carrier for preventing endwise movement of the stretcher frame while it is in horizontal position.
34. In an apparatus for stretching pieces of leather comprising an overhead runway for supporting a plurality of stretcher frames, the combination of a carrier or supporting table for removing the stretcher frames one at a time and for returning them to the runway, said carrier or supporting table comprising standards having supporting surfaces for the stretcher frame when the latter is in a horizontal position, a pair of levers pivoted to the standards and a vertically disposed member connected to the levers in such a way as to maintain them in parallel relation, said vertical member comprising a bar to serve as a support for a stretcher frame while the latter is being removed from and returned to the runway, and also to serve in connection with the supporting surfaces on the standards to support the stretcher frame when in horizontal position, and means for preventing either endwise or lateral movement of the stretcher frame on the support while it is in horizontal position.
35. In an apparatus for stretching pieces of leather comprising an overhead runway for supporting a plurality of stretcher frames, the combination of a carrier or supporting table for removing the stretcher frames one at a time and for returning them to the runway, said carrier or supporting table comprising standards, a pair of levers pivoted to the standards and a vertically disposed member connected to the levers in such a way as to maintain them in parallel relation, said vertical member serving as a support for a stretcher frame while the latter is being removed from and returned to the runway and also serving in connection with the standards to support the stretcher frame when in horizontal position, and means for preventing either endwise or lateral movement of the stretcher frame on the supporting table while it is in horizontal position.
36. In an apparatus for stretching pieces of leather comprising an overhead runway for supporting a plurality of stretcher

frames, the combination of a carrier or supporting table for removing the stretcher frames one at a time and for returning them to the runway, said carrier or supporting table comprising standards having supporting surfaces for the stretcher frame when the latter is in a horizontal position, a pair of levers pivoted to the standards and a vertically disposed member connected to the levers in such a way as to maintain them in parallel relation, said vertical member serving as a support for a stretcher frame while the latter is being removed from and returned to the runway and also serving in connection with the supporting surfaces on the standards to support the stretcher frame when in horizontal position, and means for locking the stretcher frame to the supporting table while it is in horizontal position.

37. In an apparatus for stretching pieces of leather comprising an overhead runway for supporting a plurality of stretcher frames, the combination of a carrier or supporting table for removing the stretcher frames one at a time and for returning them to the runway, said carrier or supporting table comprising standards having supporting surfaces for the stretcher frame when the latter is in a horizontal position, a pair of levers pivoted to the standards and a vertically disposed member connected to the levers in such a way as to maintain them in parallel relation, said vertical member comprising a bar to serve as a support for a stretcher frame while the latter is being removed from and returned to the runway, and also to serve in connection with the supporting surfaces on the standards to support the stretcher frame when in horizontal position, and means for locking the stretcher frame to the support while it is in horizontal position.

38. In an apparatus for stretching pieces of leather comprising an overhead runway for supporting a plurality of stretcher frames, the combination of a carrier or supporting table for removing the stretcher frames one at a time and for returning them to the runway, said carrier or supporting table comprising standards having supporting surfaces for the stretcher frame when the latter is in a horizontal position, a pair of levers pivoted to the standards and a vertically disposed member connected to the levers in such a way as to maintain them in parallel relation, said vertical member serving as a support for a stretcher frame while the latter is being removed from and returned to the runway and also serving in connection with the supporting surfaces on the standards to support the stretcher frame when in horizontal position, means for preventing either endwise or lateral movement of the stretcher frame on the supporting table while the frame is in horizontal position, and means

for locking the levers and the stretcher frame against movement while the stretcher frame is in horizontal position.

39. In an apparatus for stretching pieces of leather comprising an overhead runway for supporting a plurality of stretcher frames, the combination of a carrier or supporting table for removing the stretcher frames one at a time and for returning them to the runway, said carrier or supporting table comprising standards having supporting surfaces for the stretcher frame when the latter is in a horizontal position, a pair of levers pivoted to the standards and a vertically disposed member connected to the levers in such a way as to maintain them in parallel relation, said vertical member comprising a bar to serve as a support for a stretcher frame while the latter is being removed from and returned to the runway and also to serve in connection with the supporting surfaces on the standards to support the stretcher frame when in horizontal position, and means for locking the levers and the stretcher frame against movement while the stretcher frame is in horizontal position.

In testimony whereof I have signed my name to this specification.

GUSTAV ADOLF SCHETTLER.
